UNITED STATES PATENT OFFICE.

LEONARD E. BENSON, OF CHICAGO, ILLINOIS.

WASHBOARD.

No. 903,950.

Specification of Letters Patent. Patented Nov. 17, 1908.

Application filed December 2, 1907. Serial No. 404,769.

To all whom it may concern:

Be it known that I, LEONARD E. BENSON, a citizen of the United States, residing at Chicago, county of Cook, and State of Illinois, have invented certain new and useful Improvements in Washboards, of which the following is a specification.

My invention relates to washboards for laundry use, and the object of my invention 10 is to provide a washboard which may be readily attached or firmly fixed to a tub or similar receptacle, to the end that the board may be held perfectly firm and still, permitting the operator to use both hands.

15 Further objects of my invention are to provide a washboard having a longer rubbing surface than usual, and to provide a washboard which may be securely held within the tub without resting on the bottom.

20 A further object is to provide a washboard which may be secured to any wash-tub, either portable or stationary, and held at the proper inclination.

A further object is to provide a washboard 25 as mentioned, which shall be strong and durable and of low cost to manufacture.

Other objects will appear hereinafter.

My invention will be more readily understood by reference to the accompanying 30 drawings, forming a part of this specification and in which,

Figure 1 is a vertical section of the device embodying my invention, illustrating the same as attached to the side of a tub. Fig. 35 2 is a perspective view of the board, and Fig. 3 is a side elevation of a modified form.

Referring to the drawings, the washboard 40 comprises the board, 1, having the side bars, 2—2 and a zinc rubbing surface, 3. To the under face of the board, 1, I secure a pair of substantially triangular brackets or blocks, 4 which support the board at the proper inclination in the tub. The blocks or members, 4 are each provided with means 45 for attaching the board to the side of a tub and for securely clamping it thereto. To this end, I provide the clamp secured to each member and comprising a vertical portion 5 secured to the outer edge of the member, 4 and a horizontal offset portion, 6

which rests upon the edge of the tub and a depending portion, 7.

The device is readily placed upon a tub of any style and is securely clamped thereto by the thumb screws, 8 which are threaded 55 through the portion, 7 and impinge against the side of the tub.

The board is formed without the usual legs to rest upon the bottom of the tub, the board being supported entirely by the clamp 60 and held at the proper inclination by the bracket members, 4. However, the board is made of sufficient length to reach nearly to the bottom of the tub and the zinc washing or scrubbing surface extends to the bottom 65 of the board forming an unusually long scrubbing surface. It is obvious that as the board is held perfectly firm in the proper position in the tub, both hands are free for use. 70

Instead of forming the members, 4, of separate blocks and securing them to the board, 1 they may be formed integrally with the side bars, 2 as illustrated in Fig. 3. Either form is strong and durable and may 75 be manufactured at low cost, the blocks, 4 being formed of wood and the clamps of a strip of bar iron bent into the shape shown and described.

Having described my invention what I 80 claim as new and desire to secure by Letters Patent is:

1. A wash board, in combination with a pair of triangular blocks upon the back thereof and a clamp arranged upon each of 85 said blocks, said clamp comprising a vertical portion secured to the outer edge of the block, an offset portion adapted to rest upon the top edge of a tub to support the device out of contact with the bottom thereof, a depending portion and a thumb screw threaded through said depending portion, substantially as described.

2. A washboard having side rails in combination with a pair of solid triangular 95 blocks secured to the back of said board within said rails, and a clamp arranged upon each of said members and adapted to support said board and hold the same firmly in position, each of said clamps comprising a 100

strip of metal consisting of a straight portion secured to the outer edge of its respective triangular member, an offset portion, a depending portion and a thumb screw
5 threaded through said depending portion, substantially as described.

In testimony whereof I have signed my

name to this specification in the presence of two subscribing witnesses.

LEONARD E. BENSON.
